UNITED STATES PATENT OFFICE.

PERCY S. WARMAN, OF ROSELLE, NEW JERSEY, ASSIGNOR TO BEVERLY LIGHTS CORPORATION, OF PROVIDENCE, RHODE ISLAND, A CORPORATION OF RHODE ISLAND.

DESIGN FOR A CEILING PLATE FOR LIGHTING FIXTURES.

Application filed April 24, 1922. Serial No. 1,931. Term of patent 7 years.

To all whom it may concern:

Be it known that I, Percy S. Warman, a subject of British Empire, residing at Roselle, in the county of Union and State of New Jersey, have invented a new, original, and ornamental Design for a Ceiling Plate for Lighting Fixtures, of which the following is a specification, reference being had to the accompanying drawing, forming part thereof.

Fig. 1 is a bottom view of a ceiling plate for lighting fixtures, showing my new design.

Fig. 2 is a side fragmentary view of the same.

I claim—

The ornamental design for a ceiling plate for lighting fixtures, as shown.

PERCY S. WARMAN.
